UNITED STATES PATENT OFFICE.

JOB HUTCHINSON, OF BROOKLYN, NEW YORK.

INTERNAL-COMBUSTION ENGINE.

1,393,132.

Specification of Letters Patent. Patented Oct. 11, 1921.

Application filed March 31, 1919. Serial No. 286,466.

To all whom it may concern:

Be it known that I, Job HUTCHINSON, a citizen of the United States, residing at Brooklyn, in the county of Kings and State 5 of New York, have invented new and useful Improvements in Internal-Combustion Engines, of which the following is a specification.

This invention relates to internal combustion engines, and more particularly to engines employed for the propulsion of motor driven vehicles.

In certain of its features, the invention has to do with engines operating on the two- 15 cycle principle, but in its broader aspects it contemplates improvements which are applicable to engines of either the two-cycle or four-cycle type.

One of the primary objects of the invention 20 is to provide means operable from the driver's seat for varying the combustion space at the end of the cylinder, and hence the compression, as conditions may require.

In every engine, there is a certain definite 25 compression which produces the highest efficiency, with a given quality of fuel, and with a given density of the atmosphere. Where the grade of fuel varies it is desirable to correspondingly change the compression, and where, as in flying machine work, 30 the altitude, and consequently the density of the surrounding air, constantly varies, it is necessary for the operator to be able to adjust the size of the combustion space while 35 the machine is in motion, without leaving his seat. By means of my improved construction, the size of the combustion or compression space can either be increased or reduced, as required, and the increase of such 40 space will make possible very low throttling, and prevent condensation when kerosene is used as fuel.

A further and important object of the invention is to provide a two-cycle engine having 45 an initial compression chamber entirely separate from the crank-case, and preferably located between such crank case and the cylinder.

A further object is to provide an auxiliary 50 piston, operated from the main crank shaft, for producing a higher compression in such chamber than could be normally produced by the main or working piston alone.

A still further object of the invention is 55 to provide a two-cycle engine of the above type in which the inlet and exhaust ports to

the working cylinder are controlled wholly by the piston itself without the use of other valves.

Other objects of the invention are to arrange 60 the connecting rods so that the wrist pins and crank bearings may be easily accessible for inspection and repair without removal of the engine base or crank case, and to provide an improved pressure oiling 65 system for the various parts of the engine structure.

With the above and other subsidiary objects in view, and to improve and simplify 70 in many ways the structural details, the invention consists in the construction, combination and arrangement of parts herein-after described and claimed, and illustrated in the accompanying drawings, in which:

Figure 1 is a side elevation of a four-cylinder, two-cycle engine constructed in accordance 75 with my invention, showing the control of the combustion space from the driver's seat;

Fig. 2 is a vertical transverse section 80 through my improved engine substantially on the line 2-2 of Fig. 3;

Fig. 3 is a longitudinal section through one of the cylinders and associated parts 85 substantially on the line 3-3 of Fig. 4, parts being in elevation;

Fig. 4 is a transverse section through the engine substantially on the line 4-4 of Fig. 3;

Fig. 5 is a horizontal fragmentary section 90 substantially on the line 5-5 of Fig. 4;

Figs. 6, 7 and 8 are horizontal sections on the lines 6-6, 7-7, and 8-8, respectively of Fig. 4, parts being omitted;

Figs. 9 and 10 are vertical sectional views 95 taken in planes at right angles to each other showing a modified construction of piston and pitman rods.

Fig. 10^a is a fragmentary sectional view similar to Fig. 10, but showing a slightly 100 different construction;

Fig. 11 is a transverse section showing a modified form of engine in which there are two crank shafts geared to a common power shaft; and

Fig. 12 is a vertical transverse section 105 somewhat similar to Fig. 4 but showing a slightly modified construction, parts being omitted.

Referring to the drawings in detail, my 110 improved engine comprises a suitable base casting 1 on which the cylinders 2 are

mounted. The upper ends of the cylinders are closed by the heads 3. A pair of exhaust manifolds 4 is provided, one on each side of the engine and these are connected with 5 exhaust ports 54, hereinafter referred to, by means of the branches 4^a. To the lower part of the base 1 is secured a crank case 5 having an extended trough-shaped portion 6 which serves as an oil reservoir.

- 10 The main or crank shaft is designated at 7 and the usual fan at 8, the fan being driven from the crank shaft by means of gearing inclosed within the casing 9. This gearing also drives the shaft 10 which is coupled to 15 a water circulating pump 11 and to ignition generator 12.

The water circulating system comprises the pipe 13^a leading to the pump 11, a pipe 13 extending from the pump to the engine 20 base, and a pipe 14 which taps the upper ends of the several water jackets surrounding the respective cylinders. Referring particularly to Figs. 4 and 7 it will be seen that there is a water channel 23 extending along each 25 side of the engine base connecting with the pipe 13. The channels 23 are connected by means of cross channels 24 extending between the cylinders and are provided in their upper walls with ports 25 adapted to register with similar ports formed in the lower wall of each cylinder water jacket 26. In assembling the parts these ports are caused to register and this forms the water channels or spaces in both the engine base and 35 cylinders into a single, intercommunicating, circulating system. Since the pump 11 delivers into the channels 23 in the engine base, the cylinders with their water jackets can be removed without disturbing the pump.

- 40 15 designates the intake manifold and is clearly shown in Figs. 2 and 4. This manifold is preferably cast integral with the base structure. Fuel gas or vapor is supplied to the manifold 15 from a suitable carbureter (not shown) through the pipe 16.

The outer wall of the manifold 15 is provided with a plurality of valve seats 17, one for each cylinder, and coöperating with each of these seats is a puppet valve 18 mounted 50 on a stem 21 and urged toward its seat by means of a spring 19. This valve controls communication between the manifold 15 and the initial compression or suction chamber which I have designated 20, and the spring 55 and valve are located in such chamber. The valve stems 21 slide freely through bushings mounted in the inner wall of the manifold 15 and their inner ends ride upon cam surfaces formed on the edge of crank disks 60 22 to which the main pitman rods are connected, and which are mounted on the main shaft 7. By virtue of this construction the puppet valves are operated directly from the main crank shaft without the use of any

gearing, and the engine can run in one direction only.

The main or working piston of each cylinder is designated in its entirety by the reference numeral 27 and is of novel construction. It comprises a central body portion 70 which carries the wrist pin to which the pitman rods are secured. This wrist pin extends through opposed longitudinal slots 28 formed in the cylinder 2. It comprises a two-part hollow bushing consisting of the 75 separable sections 29 and 30 united at their middle by means of screw threaded connection 31. A pair of pitman rods 32 is provided, one being carried by each end of the wrist pin just outside of the cylinder. By 80 reason of the construction described each pitman rod may be disconnected from the wrist pin by removing the corresponding section from the outside. The lower ends of the connecting rods 32 are journaled on 85 wrist pins 33 carried between pairs of the crank disks 22.

The pitman rods and associated parts are inclosed within a casing extending between the cylinders and constructed as follows: 90 Each cylinder is provided at its sides with plates or flanges 34 which, at the bottom, where they rest upon the engine base, are substantially the same width as such base, and which grow narrower toward their upper ends. At the top of the flanges 34, and just above the upper end of the slots 28, the cylinders are provided with horizontally extending cross flanges 35 and to the flanges 34 and 35 are secured cover plates 36 and 100 37, which, as will be seen from an inspection of Figs. 1 and 2, completely inclose the space between the cylinders within which space the pitman rods operate.

The engine base structure 1 is provided 105 with a series of transverse partition walls 1^a (see Fig. 5), these walls extending down to about the level of the axis of the crank shaft, and at this level such partition walls are united in pairs by means of horizontal 110 partitions 38 also preferably cast integral with the engine base. From an inspection of Figs. 3, 4 and 5 it will be seen that the partition walls 1^a and 38 inclose a space 115 which constitutes the initial compression chamber designated by the reference numeral 20. It will be particularly noted that this space or chamber is completely cut off from the crank case 5 and forms a gas tight compartment located between such crank 120 case and the lower end of the corresponding cylinder.

The fuel gases may be drawn into and compressed in this compression chamber by means of the working piston 27 alone, if desired, but I have found it advantageous to provide auxiliary means for producing super-compression in this chamber. Such

super-compression of the charge is valuable when working in rare atmospheres and produces a more effective scavenging under other conditions. As shown in the drawing 5 and particularly in Figs. 3 and 4 thereof, the means which I have provided for producing the above mentioned super-compression comprises a piston 41 working in a short cylinder 40 open at both ends and preferably formed integral with the partition wall 38. The lower part of the cylinder 40 is formed with a lateral enlargement 39 to accommodate an eccentric 45 secured to the main crank shaft 7. A strap 44 surrounds 10 the eccentric 45 and is carried at the lower end of a pitman rod 43 which is pivoted at its upper end to a wrist pin 42 set into the piston 41. It will thus be seen that as the shaft 7 revolves the piston 41 is caused to reciprocate. It will also be noted that this 15 piston forms part of the dividing wall between the compression chamber 20 and the crank case so that any upward movement of the piston tends to decrease the capacity of such chamber and to compress its gaseous contents. It will be understood that the piston 41 moves up as the working piston 27 moves downwardly, thereby compressing the charge between them. Conversely, when the 20 working piston 27 moves upwardly the piston 41 moves down, thus producing a vacuum in the chamber 20 and drawing a fuel charge into the same through the valve port 17, the valve 18 during such time being 25 lifted by means of the cam disk 22. In practice it is desirable to so proportion the parts that the volume of gas drawn in by the combined movement of the two pistons 27 and 41 as above described, is at least equal 30 to the entire volume of the working cylinder, including the combustion space. By this means the complete expulsion of the burnt gases from the working cylinder is assured. 35 The working piston 27 is provided with a plurality of sets of packing rings 46 and preferably is formed with an extension 47 which surrounds the cylinder 40. This extension is cut away on opposite sides as indicated at 48 (see Fig. 3) so as to clear the enlargement 39 and also to insure free communication between the upper end of cylinder 40 and the chamber 20.

The inner wall of each cylinder 2 is extended slightly below the water jacket as 45 indicated at 49^a in Fig 4, and in such extension is formed a pair of diametrically opposed ports 49 communicating with the chamber 20. The piston 27 is formed with a pair of similarly disposed ports 50 adapted 50 to register with the ports 49 as shown in Fig. 4, and the ports 50 communicate with the interior of the working cylinder through passages 51 formed in the piston (see Figs. 4 and 6). It will be noted that the piston

rings 46 are arranged on both sides of the 65 ports 50 so as to prevent leakage of gas.

Forming part of the working piston 27 is a sleeve 52 which extends upwardly from the upper set of packing rings 46 and snugly fits the interior of the cylinder. This 70 sleeve is provided near its upper end with exhaust ports 53 adapted to register with corresponding ports 54 formed in the cylinder walls, which ports 54 communicate with the exhaust manifolds 4 as indicated in 75 Fig. 2.

In order to adjust the size of the combustion chamber and thus vary the compression in each cylinder as described in the preamble to the specification, I provide a 80 movable piston or abutment 55 slidably mounted in the upper end of each cylinder. Such piston or abutment works within the sleeve 52 and is equipped with piston rings 85 56 forming a gas tight joint with such sleeve. The piston 55 carries a wrist pin 57 to which is pivoted the lower end of a connecting rod 58, the upper end of which surrounds an eccentric 59 mounted on a shaft 60 which is mounted longitudinally of the engine adjacent the cylinder tops. The cam 59 and associated parts are inclosed within a housing 3^a formed on the cylinder head 3.

Projecting inwardly and axially of the cylinder from the cylinder head 3 is a tubular guide member 62 which engages the interior of the hollow piston or abutment 55 as clearly shown in Fig. 4.

Referring to Fig. 1 it will be seen that the shaft 60 controlling the movable abutments 55 is provided with a suitable coupling 61 between each pair of cylinders and is connected at one end with a suitable operating lever arranged so as to be accessible from the driver's seat. The connection 100 shown in the drawing comprises a gear 63 secured to the shaft 60 and meshing with a gear 64 which is rigidly connected with an operating lever 65. Such lever is provided with a suitable spring catch adapted to engage a notched quadrant 66 and is so mounted as to be readily accessible to the operator when occupying the driver's seat. (This is conventionally illustrated in Fig. 1 and is designated by the word "Seat"). 115

From the above it will be seen that by moving the lever 65 the operator can shift the abutments 55 so as to reduce or increase the combustion space in the cylinders as conditions may require.

The spark plugs are designated by the numeral 67 and as will be seen by reference to Fig. 4 they are set into openings in the cylinder wall. These openings are normally closed or covered by the sleeve 52 and are uncovered only when the ports 50 come into registry with such openings.

The operation of the engine as above de-

scribed will be apparent. As the piston 27 moves upwardly and the piston 41 downwardly a charge of fuel gas or vapor is drawn into the initial compression chamber 20. Then as the two pistons move toward each other such charge is compressed within the chamber 20, the compression increasing until the ports 50 are brought into registry with the ports 49 as shown in Fig. 4. At the moment that this occurs the compressed charge from the chamber 20 will flow upwardly through the ports 49 and 50 and passages 51 and fill the cylinder, driving out the spent gases through the exhaust ports 53 and 54. As the piston 27 moves upwardly again the exhaust ports are closed and the charge compressed in the working cylinder until the ports 50 uncover the spark plugs 67, and at this moment ignition takes place. It will be noted that both inlet to and exhaust from the cylinder is controlled wholly by ports formed in the piston itself and that no auxiliary valves of any kind are employed.

In order to properly lubricate the working parts of the engine I have devised an improved oiling system operating under pressure produced by a pump driven from the main shaft. Referring to Figs. 3 and 4 it will be seen that a link 68 is secured to the eccentric strip 44 and is connected at its lower end to a plunger 69 operating in a pump cylinder 70. A port 71 controlled by a spring pressed check valve 72 controls communication between the oil reservoir 6 and the pump, while a second spring check valve 73 controls the port from which oil is delivered by the pump. This port communicates with a passage 74, preferably formed in the wall of the crank case, which connects at its upper end with a distribution main or manifold 75 extending longitudinally throughout the length of the engine base. Branch conduits or ducts 76 extend from the main 75 to the various crank shaft bearings, and suitable spray nozzles 77 communicating with the main 75 are designed to sprinkle oil upon the wrist pins 33 and associated parts. Other oil ducts extend upwardly from the main 75, preferably being formed in a rib 79 cast integral with the engine base, and delivery pipes 80 extend upwardly from such ducts to a point immediately over the wrist pins 30, where they are provided with suitable nozzles 81 designed to spray oil upon such wrist pins. This spray is so directed as to enter the slots 28 in the cylinder walls and impinge against the sleeves 52 therein so as to thoroughly lubricate the inside of the cylinder. With this arrangement oil is prevented from entering the combustion chamber.

While I have shown in Figs. 2, 3 and 4 the wrist pins 30 and associated bushing as rigidly mounted in the piston 27, difficulty

may be experienced with such a construction owing to the tendency of such wrist pins to cant and bind in case of slightly unequal wear of the pitman rod bearings. To obviate this and to equalize the strain on the two pitman rods I have provided the construction shown in Figs. 9 and 10. Referring to these figures it will be seen that the wrist pin sections 29 and 30 are mounted in a yoke 82 having a downwardly extending shank portion 83 pivotally mounted at its lower end upon a suitable pin 84 carried by the piston at right angles to the wrist pin 30. By virtue of this construction it will be seen that the wrist pin structure is capable of a slight transverse oscillatory movement about the pin 84 so that inequalities of wear may be automatically compensated for and the strain on the two pitman rods equalized. In order that the slight oscillatory or rocking movement above described may take place, slots 85 are provided in the sides of the piston and the yoke 82 is formed thickest at its center and tapering outwardly toward each end as indicated at 82^a in Fig. 10.

In Fig. 10^a I have shown a still further modified construction for accomplishing the same purpose. Referring to this figure, it will be seen that I mount the wrist pin in a bushing 96 having a central spherical portion 97 which fits within the opening in the piston, so that the bushing and pin are capable of rocking relative to the piston. In this case, as also in Figs. 9 and 10, it is desirable to attach the pitman rods 32 to a connection head 98 journaled on the wrist pin, by means of a cross pivot pin 99. Instead of the two-part wrist pin shown in the other figures, I have illustrated a continuous pin to the ends of which the pitman connection heads are secured by means of bolts 100.

Referring again to Fig. 9 it will also be noted that there is illustrated a slightly different form of packing ring construction. While in Fig. 4 I have illustrated two sets of rings 46 arranged one above and one below the ports 50, I propose as an alternative construction to provide a single, relatively wide ring 86 (see Fig. 9) and to form the ports 50 directly through the body of such ring itself. With such a construction the danger of gas leaking around the cylinder between the rings and escaping from the slots 28, is eliminated.

Referring to Fig. 12, in which I have shown a slightly modified construction of cylinder and piston, the same wide packing ring 86 is illustrated. While in Fig. 4 I have shown the sleeves 52 as fitting between the abutment 55 and cylinder wall, it will be seen by reference to Fig. 12 that I propose as an alternative arrangement, a construction in which the sleeve 52' fits be-

70

tween the cylinder wall and tubular guide member 92. While in Fig. 4 the movable abutment 55 makes a gas-tight fit with the sleeve, the abutment in Fig. 12 makes a 5 gas-tight fit with the tubular guide member 92. While in Fig. 4 the upper end of the sleeve 52 has no packing rings, in Fig. 12 I have shown the upper edge of such sleeve as provided with a packing ring 94. The 10 sleeve 52' is adapted to enter the space 93 between the cylinder wall and tubular guide 92 and the piston ring 94 is preferably a rather loose fit so as to permit the escape of any gas which may be trapped in the space. 15 While in Fig. 4 I have shown the movable abutment as outside of the tubular guide and in Fig. 12 I have shown it as inside of the same, it is clear that in both constructions the sleeve 52 or 52' is disposed outside of 20 the movable abutment and between such abutment and the cylinder wall.

In Fig. 11 I have illustrated how my improved engine construction is readily adapted to an arrangement in which twin engines operate upon a common power shaft. In this figure I have shown two sets of cylinders 2^a and 2^b mounted upon a common base. The power shaft is indicated at 87 and is mounted centrally of the base 25 in a plane between the two cylinders. On this shaft is mounted a gear 88 which meshes with a pair of similar gears 89, one of which is mounted on each engine crank shaft. The same means for operating the 30 puppet valves is employed as described in connection with the other figures.

A cam or eccentric 90 is secured to the power shaft 87 and operates a spring pressed 35 plunger 69' working in a cylinder 70' and delivering oil through two check valves 73 and 73' and ducts 74 and 74' to two distribution mains 75 and 75' extending along 40 opposite sides of the engine base. It will be understood that oil supply pipes and 45 ducts from these two mains are arranged in a manner similar to that described in connection with the other figures.

What I claim is:

1. In a two-cycle internal combustion 50 engine, the combination with the cylinder, piston, and crank-case, of an initial compression chamber independent of and separate from the cylinder and crank-case, and means operated by said piston during its 55 return stroke for drawing a gaseous charge into said chamber during its working stroke and compressing the same therein.

2. In a two-cycle engine, the combination 60 with the cylinder, working piston, and initial compression chamber, of an auxiliary piston for varying the capacity of said chamber, and a movable abutment mounted in the end of said cylinder.

3. In a two-cycle engine, the combina-

tion with the cylinder, working piston, and 65 initial compression chamber, of an auxiliary piston for varying the capacity of said chamber and operable simultaneously with the working piston, and a movable abutment mounted in the end of said cylinder. 70

4. In a two-cycle engine, the combination 75 with the cylinder and piston forming between them a combustion chamber, of an initial compression chamber, means separate from said piston for varying the capacity of the initial compression chamber and additional means for varying at will the size of said combustion chamber.

5. In a two-cycle internal combustion 80 engine, the combination with the cylinder, piston, and crank-case, of an initial compression chamber separate from the crank-case and cylinder and disposed between the same, and means for delivering a combustible charge into said chamber. 85

6. In a two-cycle internal combustion engine, the combination with the cylinder, piston, and crank-case, of a pair of pitman rods extending from the piston into the crank-case and disposed one on each side 90 of the cylinder, and an initial compression chamber separate from said crank-case, and located between said pitman rods and between the cylinder and crank-case.

7. In a multi-cylinder two-cycle, internal 95 combustion engine, the combination with the base, crank-case, and cylinders mounted upon the base, of a plurality of partitions forming part of the base structure, and dividing the same into crank compartments, and initial 100 compression compartments, independent of the crank compartments.

8. In a multi-cylinder engine, the combination with a series of parallel cylinders, pistons in said cylinders, and wrist pins 105 carried by said pistons and projecting through slots in the walls of the cylinders, of pitman rods engaging the ends of said wrist pins, and a casing inclosing the ends of said wrist pins and pitman rods, said 110 casing comprising removable plates secured to and extending between the cylinders so as to completely house in a portion of the space between them.

9. In a two-cycle engine, the combination 115 with a cylinder, and compression chamber, said cylinder having an exhaust port, and an inlet port communicating with said chamber, of a single working piston comprising a unitary working structure reciprocable in 120 said cylinder and having ports wholly controlling both the inlet and exhaust ports of the cylinder, whereby the use of valves is eliminated.

10. In an internal combustion engine, the 125 combination with a cylinder having a port, of a piston fitting in said cylinder and having a relatively wide packing ring, said pis-

- ton having a port adapted to coöperate with the port in the cylinder, said piston port extending directly through the body of the ring.
- 5 11. In a two-cycle internal combustion engine, the combination with a cylinder having a port and a pair of opposed longitudinal slots, of a piston fitting within said cylinder and having a coöperating port, a wrist pin carried by said piston and projecting through said slots, and a relatively wide packing ring carried by said piston, said piston port extending directly through the body of the ring.
- 10 12. In a two-cycle engine, the combination with the cylinder, piston and an initial compression chamber entirely outside of said cylinder, of means separate from and in addition to said piston for compressing 20 the charge in said chamber.
13. In a two-cycle engine, the combination with the cylinder, piston, and a chamber entirely outside of said cylinder, in which chamber the charge is initially compressed 25 by said piston, of means separate from but acting simultaneously with said piston for increasing the compression of the charge in said chamber.
14. In a two-cycle engine, the combination 30 with the working cylinder, piston, and a chamber entirely outside of said cylinder in which chamber the charge is initially compressed by said piston, of an independent auxiliary cylinder and piston for increasing 35 the compression of the charge in said chamber.
15. In a two-cycle engine, the combination 40 with the working cylinder, piston, and crank-shaft, of an initial compression chamber into which the charge is drawn and compressed by said piston, of an independent auxiliary cylinder having a piston operated by said crank-shaft for increasing the compression of the charge in said chamber.
- 45 16. In an internal combustion engine, the combination with a cylinder having longitudinal slots, of a piston working in said cylinder, a wrist pin carried by said piston and extending through said slots, and pit- 50 man rods mounted on the ends of said wrist pin, such pin comprising two normally con-
- nected separable sections, each removable outwardly.
17. In an internal combustion engine, the combination with the cylinder, of a piston working in said cylinder, a crank-shaft, and a pair of pitman rods connecting said piston and crank-shaft and disposed one on each side of the cylinder, the means connecting said pitman rods with the piston comprising a pair of pivot pins arranged with their axes at right angles to each other.
18. In an internal combustion engine, the combination with the cylinder, of a piston working therein, a member pivoted inside 65 of said piston, a wrist pin carried by said pivoted member and projecting through the piston and cylinder walls, and a pair of pitman rods mounted on the extended ends of said wrist pin.
19. In a two-cycle engine, the combination with the usual crank case, of an initial compression chamber separate from said crank case, a valve for controlling the admission of a gaseous charge thereto, a crank-shaft, 70 and a cam on said crank-shaft for opening said valve.
20. In a two-cycle engine, an initial compression chamber, a puppet valve for controlling the admission of a gaseous charge 80 thereto, a piston, a crank-shaft, a crank-disk on said shaft, a pitman connecting said piston and crank-disk, and a cam surface on said crank-disk serving to actuate said valve.
21. In a two-cycle internal combustion 85 engine, the combination with a fuel supply conduit and initial compression or suction chamber, of a puppet valve controlling communication between said conduit and chamber, said valve having a spring located on 90 one side thereof in said chamber and a guide stem extending from the opposite side thereof, into said fuel conduit.
22. In an internal combustion engine, a cast metal base, a plurality of cylinders 95 mounted on said base, and a fuel supply manifold cast into said base and extending longitudinally thereof past each of said cylinders.

In testimony whereof I have hereunto set 100 my hand.

JOB HUTCHINSON.
